UNITED STATES PATENT OFFICE.

WILLIAM WUNSCH, OF BROOKLYN, NEW YORK.

GAME-BOARD.

1,144,927.

Specification of Letters Patent. Patented June 29, 1915.

Application filed October 16, 1914. Serial No. 866,982.

To all whom it may concern:

Be it known that I, WILLIAM WUNSCH, a citizen of the United States, residing at Brooklyn, in the county of Kings and State 5 of New York, have invented certain new and useful Improvements in Game-Boards; and I do hereby declare the following to be a full, clear, and exact description of the invention, such as will enable others skilled 10 in the art to which it appertains to make and use the same.

This invention relates to game boards, and one of the principal objects of the invention is to provide a game which will be 15 interesting to old and young and which will simulate the movements of armies and peace commissions, and will thus be instructive as well as entertaining.

Another object of the invention is to provide 20 a game board representing the fields of battle between countries and in which certain movements of armies will be made depending upon the spinning of a game piece falling into various colored fields or territories 25 having numbers thereon to indicate the movements of flags upon the game board toward and from the capitals of the countries, other movements being made on the board to represent the various positions of 30 armies and legislative bodies and peace commissions.

The foregoing and other objects may be attained by means of the construction illustrated 35 in the accompanying drawings, in which—

Figure 1 is a top plan view of the frame board and the box for containing the same connected together and ready to play the game after the flags have been placed in position, Fig. 2 is a sectional view through the board and box or dial so-called and showing the flags of three of the countries in position on the board, and Fig. 3 is a sectional view through the board when inclosed with- 45 in the box.

Referring to the drawings, the numeral 1 designates the game board, as an entirety, and 2 designates the box for containing the game board and dial to be used in connection 50 with the game board. The game board is provided with a flexible fabric loop 2^a which extends through a slot 3 in the box 2 and a metal pin 4 extends through the loop to hold the game board and box connected 55 in position to play the game. The game

board 1 is provided with a base member 1^a. Upon the upper surface of the game board is represented various countries in different colors, and in the present instance, the following countries are represented: Germany, 60 Austria, Russia, Belgium, France and Turkey. There being six countries involved in the game, as shown, there are six arms extending out into each country as shown. In the center of the board is a panel 5 with the 65 word "Session" therein and upon opposite sides of the panel are white curved border lines 6 and blue border lines 7, each provided with eyelet holes 8 and said eyelet holes are numbered 1, 3 and 5 in the upper 70 series and 2, 4 and 6 in the lower series. In the center of the panel is an eyelet hole 9. The arms extending from the forts 10 at the ends of the session panel, are made in three colors, the white arms *a*, the center 75 arms in blue *b* and the red arms *c*. These arms are each provided with a series of perforations and at the sides of the arms spaced apart for each alternate perforation are the words, "Mobilization," "War," "Charge," 80 "Bombard," and "Advance." At the outer end of each of the arms are circular devices 11 having a central perforation 12 and the legend capital and a number for said capital, Germany being numbered 1, Austria 85 numbered 2, Russia 3, Turkey 4, and France 5.

Within the box 2 are various colored panels or squares 14 and said panels are each provided with numbers, said panels 90 being colored some red, some white, some blue, and some green. In the center of this dial is a rectangular panel 15, one-half of which is colored red and the other half white and in the center of this panel is a 95 target or bull's eye 16. The panel 15 is also provided with the "Flag," the letter "M" and the numeral "6," one upon each side of the bull's eye. At points opposite the central panel are bull's eyes each entitled 100 "Forts," said bull's eyes being indicated by the numerals 17 and 18 and the fort 17 having the numerals 1, 3 and 5 indicated below the same and the fort 18 being provided with the numerals 2, 4 and 6.

The national flags are each provided with a flag staff or pole 19 and the German flag is indicated by the numeral 20. The flag staff 19 is placed in the eyelet hole 12 at the German capital. The French flag 21 is 110

placed in the eyelet hole 12 in the French capital and the Belgian flag 22 is placed in the eyelet hole 12 of the Belgian capital, and so on for each of the countries. In the 5 first eyelet hole at each side of the national flag are smaller flag staffs 23 having flags 24, 25 and 26, each containing the name of the country to which the national flag corresponds. Said flags 24, 25 and 26 being 10 disposed in the white arms or columns *a* representing peace. The war flags 26^a, 27 and 28 are mounted on a flag staff or pole 22 and said flag staffs are mounted in the columns *c* which may be called the war 15 columns. The column *b* is designated the retreat column.

The game piece comprises a spinner or top consisting of a ring 30 having a stem 31 and a spinning point 32.

20 The manner of playing the game may be briefly described as follows: The game piece is spun first in the bull's eye 16, and when the game piece falls upon the dial, the number of the panel and the color of the same indicate the movements of the flags 21, 24 25 and 25, depending upon whether the game piece falls upon white, red, blue or green. If the game piece falls on red, the small 30 national flags are moved forward and if the game piece falls on blue then the flags are moved backward or retreated. Should the game piece fall on white, the white flag is moved forward and should the game piece fall on green, the white flag or flag of peace 35 is moved backward or retreated. Should the game piece fall upon any of the figures 1, 3 or 5, the next player in order spins the top at the bull's eye 17 and should the game piece fall on any of the numbers 2, 4 or 6, 40 the game piece is spun from the bull's eye 18. The red column is called the advance column, the blue column is entitled the retreat column, and the white column is called the truce or peace column. When one of 45 the small national flags has been progressed in the perforations to the forts at the opposite side of the section panel, the player may then select which ever country he desires to favor in the game. The various 50 progressive movements of the game are made with the object of capturing the large national flags and when in certain positions, these flags are captured and the winner of the game is the one who secures the most 55 national flags.

The game board is packed within the box and the flags are also placed in the box after the pin 4 has been removed from the flexible loop and the latter pulled out of the slot 3.

60 The manner of playing the game may be varied within wide limits, and the number

of countries may be varied, any number being available.

What is claimed is:—

1. A game board comprising a dial having 65 numbers indicated on various colored panels, and a game board provided with a field having various colored portions having the names of different countries thereon, and arms extending from a central panel out into 70 said countries and provided with a circular device entitled "Capital" and a series of columns running from said capital to 75 "Forts" one at each side of the central panel, said columns being provided with eyelet holes, and flags provided with staffs for location at the capitals and for moving along the columns toward the central panel and back toward the capitals.

2. A game board comprising a dial, having 80 a number of ordinals indicated thereon in various colored panels, and a game board comprising a field representing various countries and columns extending from a central panel entitled "Session" and from 85 "Forts" at opposite sides thereof out to the capitals, large national flags inserted centrally in the capitals, small national flags adapted to be moved in perforations in the columns, small peace or truce flags to be 90 moved in the perforations in another column, and a game piece comprising a ring and stem and point to be operated on the dial to indicate the movements of the flags 95 in the columns.

3. A game board comprising a box having a dial therein, various colored panels on the dials, ordinals or numbers indicated in the panels, a centrally disposed panel having a target or bull's eye therein, forts at opposite sides of the central panel, a game piece to be spun at the center or at the forts, and a game board provided with various colored portions, each indicating a country, a central panel entitled "Session", 100 105 forts at opposite sides of the session, columns extending from said forts and provided with perforations, said columns being differently colored, and capitals at the outer ends of said columns, and flags to be located at each 110 capital to indicate the country and a smaller national flag to be moved along the columns in the perforations, and a white or peace flag to be moved in accordance with the 115 figures indicated by the game piece on the dial.

In testimony whereof I affix my signature in presence of two witnesses.

WILLIAM WUNSCH.
